Attorney

UNITED STATES PATENT OFFICE.

ARTHUR M. QUINTON, OF BOSTON, MASSACHUSETTS.

SLICING-MACHINE KNIFE GUARD.

1,402,959.

Specification of Letters Patent. Patented Jan. 10, 1922.

Application filed November 4, 1921. Serial No. 512,787.

To all whom it may concern:

Be it known that I, ARTHUR M. QUINTON, a citizen of the United States, residing at Boston, in the county of Suffolk and State 5 of Massachusetts, have invented certain new and useful Improvements in Slicing-Machine Knife Guards, of which the following is a specification.

This invention relates to machines for 10 slicing meat or other articles, of the type employing a slicing knife in the form of a revolving disc provided with a peripheral cutting edge; and more particularly it relates to a guard for protecting said cutting 15 edge for the avoidance of accidental injury to the machine operator or others.

While the application of a guard to the 20 knife of a slicing machine is not novel, the said guards, so far as hitherto known to me, have been made of a definite and fixed length, and have been arranged to protect only that 25 portion of the circumference of the rotating knife which is not at any time utilized in the cutting process. The portion of the 30 knife periphery by which the cutting is performed has hitherto remained exposed at all times, and unprotected by the guards of the prior types, when the machine is inoperative or idle; and by reason of the lack of 35 protection such exposed peripheral portion is at all times a menace of accidental injury to the operator and to others.

The object of my invention is, therefore, to 40 devise and produce a guard for slicing machine knives of the type described, which not only serves to afford at all times a protection for the inoperative portion of the 45 periphery of the cutter, but which also embodies a construction providing means where by an easily manipulated guard for the cutting portion of said knife periphery may be temporarily supplied at such times as the machine is not performing its cutting 50 functions.

To the attainment of this end and the accomplishment of the object above described, 55 my invention consists in the novel construction and arrangement of the several parts hereinafter more fully described and claimed; and as shown in the drawings accompanying this specification and illustrating this my invention in the said drawings:

Fig. 1 is a view in side elevation of a 60 guard embodying my invention showing the 65 parts thereof as arranged when the machine

is operating and affording protection for the inoperative portion only of the knife periphery.

Fig. 2 is a view in rear elevation of the 60 knife guard and support shown in Fig. 1.

Fig. 3 is a view similar to that of Fig. 1, showing the guard arranged to protect a larger portion of the knife edge periphery; as when the machine is idle.

Fig. 4 is a sectional view on an enlarged 65 scale, taken in the line 4-4 in Fig. 3.

Referring more particularly to the drawings the numeral 10 designates the revolving knife or cutter, in the form of a circular metal disc having its periphery beveled to 70 a cutting edge. Said knife 10 is arranged to rotate upon an axial shaft 11, which is mounted in suitable bearings and connected with appropriate means for causing the rotation of said shaft 11 and knife 10 at the 75 desired speed. The latter features are well known in the art, and are therefore not shown in the drawings; neither is it deemed necessary to detail the further description of the 80 same, nor of the other features of the cutting machine in fuller particularity.

On the frame of the machine, of which only a small portion is indicated at 12, is carried a guide support 13; to which support is attached, as by cap screws 14, the 85 outer portion 15 of the knife guard; suitable bosses secured upon the side of said outer portion near its extremities providing threaded openings within which said cap 90 screws engage.

Said outer knife guard portion is preferably formed from tubing curved in an arc corresponding with the curvature of the peripheral edge of the cutting knife; which edge is adapted to enter within the interior 95 of said guard through a slot extending longitudinally of the said outer guard portion along its inner edge, all as more clearly appears in Fig. 4.

Said guard portion 15 is so located and is 100 of such a length, that it encloses and protects the inoperative part of the slicing knife; which is assumed in Figs. 1 and 3 to comprise essentially the right hand portion thereof:

Within the said outer portion 15 of said 105 guard is enclosed and supported an inner or sliding guide portion 17, also constructed preferably of tubing and curved concentrically with the tubing of the said outer por-

110

tion. The tubing of which the outer and inner guide portions are constructed are of such relative sizes that the inner portion fits within the outer portion with a close but 5 easily sliding fit, so that the two portions readily telescope together; the inner portion within the outer.

The inner edge of said inner guide portion 17 is slotted for its entire length; such slot 10 being in substantial registration with the slot formed in the outer portion, and both being adapted to permit the peripheral edge of the cutting knife to enter within both said guide portions, all as is more clearly 15 shown in Fig. 4.

The outer edge of said outer guards portion is also provided with the slot 18, extending for a portion of its length, as for example along the arc A. Said slot is 20 adapted to receive and to permit the free travel therein of the shank of a clamp screw 19 of which the threaded end engages the block 20 secured upon the inside of the inner guide portion 17.

25 The relative lengths of the outer and inner guide portions, the extent of the slot and the location of said threaded block 20 are all so correlated that, at one end of the range of travel of the clamp screw the inner guard portion 17 is fully telescoped with the outer portion 15, as it appears in Fig. 1, and the operating portion of the peripheral edge of the cutter is exposed for the performance of its cutting functions, the inner guard portion 17 being retained in such position by the binding action resulting from the tightening of the clamp screw 19.

When, however, the slicing machine is 40 idle, the releasing of the said clamp screw 19 permits its knurled knob to be employed as a handle by which the inner guide portion 17 may be made to slide longitudinally within and to be extended from the outer (and fixed) guide portion 15; such extension carrying the inner guard 17 around the operating part of the peripheral knife edge to the desired extent; which is determined by the clamp screw 19 reaching the end of the travel permitted by the length of the 45 slot 18. In such position the said inner guard portion may be locked by the tightening of the binding screw 19; thus affording a temporary protection for the exposed portion of the knife edge, and one of a type 50 which may be in turn readily removed, as by the simple process of loosening the binding screw 19, and by means of the knob thereof, causing the inner guard portion to be withdrawn from its extended position 55 over the knife edge and to become telescoped within the said outer guard portion. While tubing of circular cross section is preferably 60

employed in the construction of the outer and inner portions of my knife guard, said portions may be constructed of tubing of 65 various cross sectional forms, and of material other than tubing, but properly the equivalent thereof when employed in the manner hereinabove described.

Having described my invention what I 70 claim and desire to secure by Letters Patent is:

1. A knife guard for a slicing machine knife of the type of a disc having a peripheral cutting edge, comprising a fixed portion, 75 a movable portion slidably mounted within said fixed portion in a telescoping relation therewith and with capacity for longitudinal extension therefrom, both said portions being arranged in their telescoped relation to 80 enclose and cover said peripheral edge along the inoperative portion of said knife, and the movable portion being arranged when extended from said fixed portion to enclose and cover said peripheral edge along the 85 portion of the knife which is used in cutting when the slicing machine is operative.

2. A knife edge for a circular cutting knife or the like having a peripheral cutting edge, comprising a fixed portion and a movable portion slidably mounted therein, both 90 said portions being curved and positioned substantially concentrically with said knife edge, said movable portion being arranged to freely telescope within said outer portion 95 or to be extended therefrom, both said portions being provided with longitudinal slots permitting said knife edge to be entered into the interior of both thereof, said outer portion being so located as to permanently 100 enclose the inoperative portion of the knife, and the movable portion being arranged when extended from said outer portion to enclose and cover said peripheral edge along the portion thereof employed for cutting 105 when the machine is operating.

3. A knife guard for a slicing machine knife in the form of a disc having a peripheral cutting edge, comprising a tubular outer portion curved concentrically with said peripheral edge and an inner tubular portion 110 adapted to fit within said outer portion and longitudinally slotted to permit said knife edge to be entered within and enclosed thereby, said outer portion being so located 115 as to permanently enclose the inoperative portion of the knife, and the inner portion being arranged when extended from said outer portion to enclose and cover said peripheral edge along the portion thereof utilized for cutting when the machine is operating.

ARTHUR M. QUINTON.
